(57) **CLAIM**

The ornamental design for an eyeglass display rack, as shown and described.

DESCRIPTION

FIG. 1 is a front left perspective view of an eyeglass display rack, showing our new design.

FIG. 2 is a front left perspective view of the design shown in FIG. 1;

FIG. 3 is a frontal view of the design shown in FIG. 1;

FIG. 4 is a rear view of the design shown in FIG. 1;

FIG. 5 is a left side view of the design shown in FIG. 1;

FIG. 6 is a right side view of the design shown in FIG. 1 and shows dotted line 7 to delineate a section;

FIG. 7 is an exploded view of the section within dotted line 7 of FIG. 6, to show the perforated nature in the part of the design shown;

FIG. 8 is a top plan view of the design shown in FIG. 1; and

FIG. 9 is a bottom plan view of the design shown in FIG. 1;

FIG. 10 is a front perspective view of a second alternate embodiment of an eyeglass display rack, showing our new design therefor;

FIG. 11 is a front left perspective view of the design shown in FIG. 10;

FIG. 12 is a frontal view of the design shown in FIG. 10;

FIG. 13 is a rear view of the design shown in FIG. 10;

FIG. 14 is a left side view of the design shown in FIG. 10;

FIG. 15 is a right side view of the design shown in FIG. 10 and shows dotted line 16 to delineate a section;

FIG. 16 is an exploded view of the section within dotted line 16 of FIG. 15, to show the perforated nature in the part of the design shown;

FIG. 17 is a top plan view of the design shown in FIG. 10; and,

FIG. 18 is a bottom plan view of the design shown in FIG. 10.
